UNITED STATES PATENT OFFICE

150,501

DESIGN FOR A LOCKET OR SIMILAR
ARTICLE

Adolph Katz, Providence, R. I., assignor to Coro,
Inc., New York, N. Y., a corporation of New
York

Application June 14, 1947, Serial No. 139,698

Term of patent 7 years

(Cl. D45—15)

To all whom it may concern:

Be it known that I, Adolph Katz, a citizen of the United States of America, residing in Providence, county of Providence, and State of Rhode Island, have invented a new, original, and ornamental Design for a Locket or Similar Article, of which the following is a specification, reference being had to the accompanying drawing, forming part thereof.

Fig. 1 is a front elevational view of a locket showing my new design.

Fig. 2 is a side elevational view thereof; and

Fig. 3 is a perspective view of the locket in an open position.

The back of the locket is substantially the same in appearance as the front as shown in Fig. 1.

I claim:

The ornamental design for a locket or similar article, substantially as shown and described.

ADOLPH KATZ.
